UNITED STATES PATENT OFFICE

2,434,538

CONTROL DEVICE

Cyril E. Baston, Irwin, Pa., assignor to Westinghouse Electric Corporation, East Pittsburgh, Pa., a corporation of Pennsylvania

Application May 16, 1944, Serial No. 535,837

2 Claims. (Cl. 200—82)

1

My invention relates, generally, to control devices and, more particularly, to fluid-pressure operated switches of the type utilized in railway control systems.

The use of groups of cam switches for the completion of electrical circuits in railway control systems has been somewhat restricted because of the difficulty of providing a means for driving the cam shaft which would not tend to stall and avoid having two or more switches closed at the same time. In spite of this problem, cam switch groups have been utilized since their use eliminates a large amount of electrical interlocking which is a potential cause of control failures.

An object of my invention, generally stated, is to provide a control switch which shall be simple and efficient in operation and which may be economically manufactured and installed.

A more specific object of my invention is to provide for accurately controlling the operation of a fluid-pressure operated switch.

Another object of my invention is to make the switch follow closely the movement of a controlling cam.

Other objects of my invention will be explained fully hereinafter or will be apparent to those skilled in the art.

In accordance with one embodiment of my invention, the force for closing a switch is supplied by fluid pressure acting upon a piston in a cylinder, but the valve for admitting the fluid to the cylinder is controlled by a cam. The switch movement must follow that of the cam exactly or mechanical interference will stop any further motion of the cam, thereby preventing improper operation of other switches controlled by the same cam shaft.

For a fuller understanding of the nature and objects of my invention, reference may be had to the following detailed description, taken in conjunction with the accompanying drawing, in which the single figure is a view, partially in section and partially elevation, of a portion of a switch unit embodying my invention.

Referring to the drawing, the structure shown therein comprises a switch cylinder 10, having a piston 11 disposed therein for actuating a movable contact member 12 into engagement with a fixed contact member 13 when a suitable pressure fluid, such as compressed air, is admitted into the cylinder 10. The piston 11 is attached to the lower end of a hollow piston rod 14, the upper end of which is attached to the moving contact member 12 by means of a bracket 15, an

insulator 16 and a bracket 17 for pivotally supporting the contact member 12. A piston spring 18 is disposed inside the cylinder 10 and is compressed when the piston is forced upwardly by the fluid pressure. The stored energy in the spring 18 forces the piston downwardly when the pressure fluid is permitted to escape to atmosphere.

In order to control the supply of pressure fluid to the cylinder 10, a valve 21 may be disposed inside of the hollow piston rod 14. The valve 21 is provided with a rod 22, the upper end of which is connected to one end of a lever 23 which is fulcrumed at 24. The other end of the lever 23 carries a roller 25 which is disposed in a groove 26 in a plate cam 27. The cam 27 may be rotated by a shaft 28 which may be driven by any suitable means, such as an electric motor.

In order to facilitate the manufacture and assembly of the hollow piston rod 14 and the valve 21, the rod 14 may be constructed of a plurality of sections which may be threaded together in the manner shown. When the piston rod and the valve are assembled, the piston 11 may be secured to the lower end of the rod by a nut 29 and the piston rod inserted into the cylinder 10 through the bottom of the cylinder, after which a cap 31 may be threaded onto the lower end of the cylinder 10. The rod 14 slides in suitable packing washers 32 and 33 which are retained in position in the lower and the upper ends of a sleeve 30 in the cylinder 10 by threaded caps 34 and 35, respectively.

The operation of the switch is as follows: When the switch members are in the position shown, the space within the cylinder 10 is in free communication with the atmosphere through the hollow piston rod 14, past the valve 21 and the piston rod 22 and out through the bracket 15. Assume now that the cam 27 is rotated in the direction of the arrow until the roller 25 is at the point 37 in the groove 26. The first downward movement of the roller 25 moves the valve rod 22 upwardly, thereby closing the valve 21 against a seat 36 and removing it from a seat 38. This permits the pressure fluid to enter the cylinder 10 through a suitable connection 39, up past the valve seat 38, and down through the hollow piston rod 14 to the lower side of the piston 11.

As the piston 11 moves upwardly, the valve 21 is held against the upper seat 36 by the continued rotation of the cam 27. In order to insure that the valve 21 is held tightly against its seat at all times, the lever 23 may be constructed of spring steel and the cam 27 so de-

signed that the lever 23 is flexed slightly at all times to maintain pressure on the valve 21.

The continued rotation of the cam 27 to a point 41 or rotation in the opposite direction moves the valve 21 against the valve seat 38 and away from the seat 36, thereby shutting off the supply of pressure fluid and venting the cylinder 10 to atmosphere to permit the spring 18 to open the contact members of the switch, as explained hereinbefore. It will be understood that the groove 26 may be so disposed in the cam 27 that the desired operation of the switch will be obtained as the cam 27 is rotated by the shaft 23.

It will also be understood that additional cams may be driven by the shaft 28 to control additional switch units of the type herein described. In this manner, a plurality of switch units may be operated in any desired sequence.

The force required to move the valve 21 is relatively small, thereby requiring a relatively small motor or other device for driving the cam shaft 28. However, the force operating to close the switch may be made as large as required by proper proportioning of the cylinder 10 and the piston 11.

If for any reason the switch movement does not follow the movement of the cam after the valve 21 has been operated, further movement of the cam shaft is prevented by the roller 25 engaging the side of the groove 26, thereby stalling the shaft 28, and the improper operation of any additional switches, controlled by the cam shaft 28 is prevented. The shaft 28 may be released from its driving means by a slip clutch, or other suitable device, which may be so constructed that it will not transmit sufficient torque to overcome the force of the spring 18.

In this manner the advantages of a group of cam-operated switches are obtained without any of the attendant disadvantages of previously known structures. Furthermore, it is not necessary to provide a large number of electrical interlocks in order to insure the proper operation of a group of switches.

Since numerous changes may be made in the above-described construction, and different embodiments of the invention may be made without

departing from the spirit and scope thereof, it is intended that all matter contained in the foregoing description or shown in the accompanying drawing shall be interpreted as illustrative and not in a limiting sense.

I claim as my invention:

1. In a fluid-pressure operated switch having a movable contact member, in combination, a cylinder, a piston disposed in the cylinder for actuating said movable contact member, valve means disposed within the cylinder and movable with said piston for controlling the supply of fluid to the cylinder, cam means disposed externally of the cylinder for controlling the operation of said valve means, and a resilient lever arm having one end engaging said cam means and the other end engaging said valve means.

2. In a fluid-pressure operated switch having a movable contact member, in combination, a cylinder, a piston disposed in the cylinder for actuating said movable contact member, valve means disposed within the cylinder and movable with the piston for controlling the supply of fluid to the cylinder, a rotatable cam disposed externally of the cylinder for controlling the operation of said valve means, a shaft for rotating said cam, and a resilient lever arm having one end engaged by said valve means for stopping the rotation of said shaft, said lever arm being actuated by said cam to operate said valve means.

CYRIL E. BASTON.
